UNITED STATES PATENT OFFICE.

WALTER H. COTTON, OF CHICAGO, ILLINOIS.

HYDROPLANE.

1,257,678.

Specification of Letters Patent. Patented Feb. 26, 1918.

Application filed April 30, 1917. Serial No. 165,456.

To all whom it may concern:

Be it known that I, WALTER H. COTTON, a citizen of the United States, and resident of Chicago, county of Cook and State of Illinois, have invented certain new and useful Improvements in Hydroplanes, of which the following is a specification, and which are illustrated in the accompanying drawings, forming a part thereof.

10 The invention relates to marine vessels of the hydroplane type; and its object is to provide a construction of the hull and of the propelling mechanism which will insure high efficiency both in speed and control.

15 An embodiment of the invention is hereinafter described, and is illustrated in the accompanying drawings in which—

Figure 1 is a side elevation of the vessel; Fig. 2 is a plan view thereof, some portions being broken away;

20 Fig. 3 is a detail sectional view on the line 3—3 showing a portion of the hull in elevation; and

Fig. 4 is a front elevation of the vessel. 25 The prow 10 of the vessel has a flat bottom 11, and is sharply upwardly inclined and at its lateral margins 12, 13, is inclined upwardly. From the rear end of the upwardly inclined prow the bottom 14 extends backwardly in a straight line, and in the normal position of the boat will be horizontal. Within the body of the hull is a well 15, as shown, extending a little forward of the rearward end of the upwardly inclined prow 30 bottom and extending backwardly a sufficient distance to accommodate the driver's seat 16 and the motor 17, and being sufficiently commodious to provide space for a mechanician or motor driver. A fuel tank 18 is carried in the body of the vessel back 35 of the well 15.

40 The motor shown is a gas engine having its axis longitudinal of the hull, and may be of any preferred type and will have the necessary appurtenances of a device of this character. A transverse shaft 19, forward of the motor, is driven thereby and projects into the wheel casings generally designated by the numerals 20, 21. Within each of 45 these casings and fixed upon the shaft 19 is a blast wheel 22. The wheel casings are segmental in form, being open at their peripheries through a segment of upward of ninety degrees, and having an outer closed 50 side 23 and an inner side wall 24 which is closed except that it is provided with a cen-

tral aperture or eye 25. These casings are rotatably mounted concentrically with the shaft 19, and each is controlled by means of a pinion 26, meshing with a gear rack 27 fixed to the outer face of the casing, each of these pinions being mounted upon a shaft 28 extending into the well 15 and controlled by a hand wheel 29 within easy reach of the operator occupying the seat 16. By means of this gearing the operator may shift each of the casings 20, 21, to the dotted lines position of Fig. 3.

The vessel is provided with a pair of laterally disposed rudders 30, 31, located one immediately back of each of the wheel casings and normally occupying a horizontal position and being so held by a torsion spring 32. A cable 33, wound upon a drum formed on the hub of each of the rudders 34 and upon a drum 34 adjacent the seat 16 and controlled by a hand wheel 35, affords means for turning the rudder downwardly to the dotted lines position of Fig. 3.

A pair of air ports 36, 37, open through the top of the prow, each leading backwardly to the eye 25 of one of the wheel casings. At the rearward end of the prow, and adjacent its juncture with the wheel casings, ports 38 are provided to permit the discharge of water which may find its way into the ports 36, 37,—a trapping plate 39 being preferably placed above these ports.

The deck 40 of the stern portion of the vessel, extending backwardly from the well 15, inclines downwardly and meets the bottom 14 at the stern 41, thereby practically eliminating stern resistance to the advance of the vessel. The forward deck 42 and the after deck 40 provide ample space for carrying fire-arms, such as machine guns. 95

When at rest the downwardly projecting blades of the blast wheels will be partially submerged. In starting the wheel casings are shifted to the dotted lines position of Fig. 3, and by the rotation of the blast wheels are quickly emptied of water, the small volume contained therein forming but slight resistance to the rapid acceleration of the engine speed. The blast wheels will be driven at high speed and induce a flow of air through the ports 36, 37, and the casing eyes 25, discharging the air backwardly and driving the vessel forward. The inclined prow acting as a plane raises the vessel to the surface, whereupon the operator restores the wheel casings to the solid lines position 105 110

and the air is driven by the blast wheels downwardly and backwardly upon the water, causing the vessel to travel forwardly at a high speed, the suction through the 5 ports 36, 37, contributing to this movement. In steering, one of the rudder blades 30, 31, is turned downwardly and, offering a resistance to the rearwardly driven air, causes the vessel to turn in its course.

10 The vessel is, therefore, air driven and controlled and because of its shape develops a minimum of skin friction or hull resistance as it moves over the surface of the water, and a very high speed may be developed with a comparatively small motor.

While an operative and preferred form of construction is shown and described, various changes of detail may be made without departing from its scope. For example, while 20 the bodily rotative wheel casings are shown, it is obvious that any means for temporarily closing their bottoms to facilitate starting may be employed.

Nor do I limit myself, in the broader aspects of the invention, to a structure in 25 which the blast wheels are so located as to enter the water when the boat is at rest and thus require means for temporarily closing the bottom of the casing. While a pair of 30 blast wheels is shown, a single wheel properly disposed would come within the scope of the invention. Again, the particular shape and size of the discharge opening from the wheel casing is discretionary.

35 I claim as my invention—

1. In a hydroplane, in combination, a hull, a blast wheel at each side of the hull, a casing covering each wheel, and an air duct open through the prow of the hull and leading 40 to each wheel casing.

2. In a hydroplane, in combination, a hull, a blast wheel at each side of the hull, a rotatively adjustable segmental casing covering each wheel, and an air duct open through 45 the prow of the hull and leading to each wheel casing.

3. In a hydroplane, in combination, a hull, a blast wheel at each side of the hull, a casing covering each wheel and normally open 50 at the bottom, means for inclosing the bottoms of the wheels, and an air duct open through the prow of the hull and leading to each wheel casing.

4. In a hydroplane, in combination, a hull, a blast wheel at each side of the hull, a rotatively adjustable segmental casing covering each wheel, an air duct open through 55 the prow of the hull and leading to each wheel casing, and means for adjusting the casings.

60 5. In a hydroplane, in combination, a hull,

a blast wheel at each side of the hull, a casing covering each wheel, an air duct open through the prow of the hull and leading to each wheel casing, and a horizontally pivoted rudder blade at each side of the hull. 65

6. In a hydroplane, in combination, a hull, a blast wheel at each side of the hull, a casing covering each wheel, an air duct open through the prow of the hull and leading to 70 each wheel casing, and a horizontally pivoted rudder blade at each side of the hull immediately back of the casings.

7. In a hydroplane, in combination, a hull, a blast wheel at each side of the hull, a 75 casing covering each wheel, an air duct open through the prow of the hull and leading to each wheel casing, a horizontally pivoted rudder blade at each side of the hull, and means for independently operating the rudder 80 blades.

8. In a hydroplane, in combination, a hull, a blast wheel at each side of the hull, a casing covering each wheel, an air duct open through the prow of the hull and leading to 85 each wheel casing, a horizontally pivoted rudder blade at each side of the hull, and means for maintaining the rudder blades normally in the same plane.

9. In a hydroplane, in combination, a hull, a blast wheel at each side of the hull, a casing covering each wheel, an air duct open through the prow of the hull and leading to 90 each wheel casing, a horizontally pivoted rudder blade at each side of the hull, and means for normally maintaining the rudder 95 blades substantially horizontal.

10. In a hydroplane, in combination, a hull having the bottom of its prow upwardly inclined and the after part of its body tapering horizontally, its deck and bottom meeting at the stern, a pair of incased side blast wheels, and air ducts leading from and open at the prow and discharging into the wheel casings. 100

11. An air driven hydroplane comprising, in combination, a hull having an inclined bottom, an incased air propelling wheel discharging upon the surface of the water, and an air duct leading to the casing. 105

12. An air driven hydroplane comprising, in combination, a hull having a bottom inclined at its forward end, an incased air propelling wheel discharging upon the surface of the water, and an air duct leading to 110 the casing.

13. An air driven hydroplane comprising, in combination, a hull, an incased air propelling wheel discharging upon the surface of the water, and an air duct leading to the 115 casing.

WALTER H. COTTON.
